UNITED STATES PATENT OFFICE.

CLARK T. HENDERSON, OF MILWAUKEE, WISCONSIN, ASSIGNOR TO THE CUTLER-HAMMER MFG. CO., OF MILWAUKEE, WISCONSIN, A CORPORATION OF WISCONSIN.

WORK-SUPPORT FOR CUTTING-MACHINES.

1,233,355.

Specification of Letters Patent. Patented July 17, 1917.

Application filed August 8, 1914. Serial No. 855,825.

To all whom it may concern:

Be it known that I, CLARK T. HENDERSON, a citizen of the United States, residing at Milwaukee, in the county of Milwaukee and 5 State of Wisconsin, have invented new and useful Improvements in Work-Supports for Cutting-Machines, of which the following is a full, clear, concise, and exact description, reference being had to the accompanying 10 drawing, forming a part of this specification.

This invention relates to machines for shearing steel products. More particularly the invention relates to an improved work support for such machinery which is adapted 15 to clamp the material thereon in accordance with the position of other parts of the mechanism.

The primary object of the invention is to provide safety means for such devices for 20 preventing manipulation of the material to be cut after the shearing blade starts to descend whereby danger of injury to the workmen is reduced.

Other objects and advantages will appear 25 hereinafter from the description of an embodiment of the invention schematically shown in the accompanying drawing, which represents a shearing machine for steel mill work together with a circuit arrangement 30 for controlling a part thereof.

The cutting machine as represented comprises a blade 1 fixed to a carrier 2 and adapted to reciprocate in a guiding frame 3 toward and from a work table 4 which supports the material to be cut, for example, 35 a steel plate 5. The carrier 2 is connected by a link 6 with an operating eccentric cam 7 on a driven shaft 8. A suitable clutch device (not shown) is provided to establish 40 driving connection between the power supply and the driven shaft 8. This clutch is of a type wherein the driving connection is maintained during only one reciprocation of the cutting blade and is arranged to be 45 actuated by a foot pedal 9. When the pedal 9 is depressed the blade 1 is driven to cutting position and returned to initial position, and then the driving connection is automatically interrupted so that the blade 50 remains elevated until the clutch is again moved.

The work support 4 is provided with a magnet winding 10 to be energized at each establishment of the driving connection with 55 the shaft 8 and to be deenergized when the

blade 1 has passed cutting position. One arrangement for accomplishing this result comprises a switch 11 adapted to complete the circuit of the winding 10 by depression of the pedal 9 and automatically actuated 60 to interrupt the winding circuit by means associated with the shaft 8 for operation in accordance with a predetermined position of the blade 1. As shown, the switch is fixed on a spindle 29 which also has fixed thereon 65 a ratchet wheel 12 adapted for operation by a pawl 13 on a lever 14 and by a pawl 15 on an independent lever 16. The lever 14 is connected for actuation by the clutch pedal 9 and is raised to normal position by a 70 spring 17. The lever 16 is provided with a roller 18 riding on a cam 19 on the shaft 8 in an arrangement so that the pawl 15 is moved to open the switch when the blade 1 is 75 completed its cutting operation and is ready for its return to upper position.

The circuit diagram illustrated is simple and obvious. The winding 10 is connected to a line 20 by conductor 21, and by conductor 22 to a switch contact 23 and thence 80 through the switch and contact 24 by conductor 25 to the other line 26. The winding is also connected with line 26 by a conductor 27 and hand switch 28 for independent closure of the winding circuit. As above 85 mentioned, the winding is energized when the clutch pedal 9 is depressed so that the work table is thereupon magnetized and firmly attracts thereto the magnetic material 5 to be cut. Manual positioning of the 90 material 5 is thus prevented after the drive of the cutting blade 1 is commenced, and the material is maintained clamped to the support until the cutting operation has been completed. Deenergization of the winding 95 10 and release of the plate 5 is thereupon accomplished by automatic interruption of the winding circuit through operation of the switch 11 by the lever 16. The plate 5 may then be freely manipulated and positioned until depression of the clutch pedal 9 again establishes the drive of the cutting blade and simultaneously effects the magnetization of the work support 4.

What I claim as new and desire to secure 105 by Letters Patent is:

1. In combination, a work support, means associated therewith to secure work thereto, a cutting device to operate upon the work carried by said support and means to estab- 110

lish a driving connection for said device and to control said work securing means to insure action thereof upon establishment of such driving connection, said work securing means being controllable by said device for release of the work after cutting thereof.

2. In combination, a work support for magnetic material, electro-responsive means associated with said support for holding the material, movable means for acting upon the material, and means insuring the energization of said electro-responsive means when said movable means is actuated.

3. In a cutting machine, in combination, a support for material to be cut, a cutting device for such material arranged to be driven by power, means to establish a driving connection therefor, and means insuring against positioning of the material to be cut after the driving connection of said device is established.

4. In a cutting machine, in combination, a support for magnetic material to be cut, a magnet winding associated with said support for holding material thereon against movement, a driven tool for cutting the material, and means to energize said magnet winding when said tool is driven toward cutting position.

5. In a cutting machine for magnetic material, in combination, a support for the material, electro-responsive means associated with said support for holding the material thereon, and movable means for cutting the material but operable only after the energization of said electro-responsive means.

6. In combination, a work support, electromagnetic means for securing work to said support, a cutting device to operate upon the work carried by said support, a control member to establish a driving connection for said device and control means for said electromagnetic means operable by said member to insure inclusion of said electromagnetic means in circuit upon establishment of such driving connection, said control means being further operable by said device after cutting operation to effect deenergization of said electromagnetic means for release of the work.

In witness whereof, I have hereunto subscribed my name in the presence of two witnesses.

CLARK T. HENDERSON.
